United States Patent Office

Des. 198,519
Patented June 23, 1964

198,519

TIRE

Joseph F. McLellan, 3202 Rowena Drive,
Los Alamitos, Calif.

Filed Mar. 4, 1963, Ser. No. 73,810

Term of patent 14 years

(Cl. D90—20)

FIG. 1.

FIG. 2.

FIG. 3.

FIGURE 1 is a perspective view of a tire showing my new design;

FIGURE 2 is a diametrical sectional view thereof; and

FIGURE 3 is an enlarged, fragmentary sectional view taken along the line 3—3 of FIGURE 2.

The dominant features of my design reside in the portions shown in full lines.

I claim:

The ornamental design for tire substantially as shown and described.
